DESIGN FOR A GRINDER

Merrill K. Apple, Oakland, Calif., assignor to
McCaldry, Inc., Oakland, Calif., a corporation
of California

Application September 10, 1946, Serial No. 133,223

Term of patent 3½ years

(Cl. D37—1)

To all whom it may concern:

Be it known that I, Merrill K. Apple, a citizen of the United States of America and a resident of the city of Oakland, county of Alameda, State of California, have invented a new, original, and ornamental Design for a Grinder, of which the following is a specification, reference being had to the accompanying drawing, forming a part thereof.

Figure 1 is a perspective view of the grinder, showing my new design, the angle of view being slightly above and to the front of the grinder;

Figure 2 is another perspective view thereof, the angle of view being slightly above and to the rear of the grinder.

I claim:
The ornamental design for a grinder, substantially as shown.

MERRILL K. APPLE.
